SOCKET FOR HIGH VOLTAGE GASEOUS
DISCHARGE TUBES

Robert E. Barclay, Chicago, Ill.

Application June 7, 1940, Serial No. 339,287

11 Claims. (Cl. 173—328)

This invention relates to a connector box or socket for high voltage gaseous discharge tubes.

An object of the invention is to provide a connector box or socket for high voltage gaseous discharge tubes which shall be simple and inexpensive from the manufacturer's standpoint; which shall be capable of ready mounting in any place where such tubes may be used and of such construction that it may be used in exposed places without detraction from the appearance of the tube installation.

Another important object of the invention is to provide a connector box of this character offering the maximum of protection against possibility of any article inadvertently or intentionally being brought into contact with the tube supplying terminals or connecting leads, and to preclude the possibility of any unauthorized person inadvertently or intentionally contacting such terminals or connecting leads.

It is also an object of applicant's invention to provide a connector box or socket for the gaseous discharge tubes, which box or socket is comprised of parts readily separable for the simple insertion and automatic connection of the discharge tube, and which separable parts are automatically latched against detachment when brought into normal assembled relation, and wherein the separable latching means may be released or unlatched only by means of a special tool thereby preventing access except by those familiar with the construction of the connector box or socket.

Applicant's invention also contemplates the provision of connector boxes or sockets for receiving and connecting in series adjacent lengths of tubing arranged in linear succession or in angular succession.

A further object to applicant's invention is to provide connector boxes or sockets for gaseous discharge tubes by which tube sections may be connected in series or by which power connections may be made to a tube or tube sections.

It is still another object of the invention to provide a connector box or socket for adjacent tube sections and in which means is provided for shielding the tubes against accumulation of static charges on adjacent or abutting end portions and thereby eliminating radio interference currents in tube installations and also eliminating the possibility of electrical shock of a person intentionally or inadvertently contacting one or both of abutting end portions of adjacent tube sections.

It is also an object of applicant's invention to provide in a connector box or socket for high

voltage discharge tubes means for eliminating dangerous "skin currents" along the tube envelopes, and also thereby increasing the life of the tubes.

5 The invention further contemplates the provision, in a connector box or socket of the above stated character, of spring clips for receiving and establishing electrical connection with the terminal tips of the discharge tube and wherein 10 means is provided for insuring the maintenance of electrical connection regardless of all mechanical vibration of the tube or socket relative to each other.

15 A further and important object of the invention is to provide a connector box or socket of the above stated character which is comprised of relatively separable parts which, when brought into assembled relation, are automatically latched against detachment by a multiplicity of latching 20 members so that operation of one of the latching members will not permit separation of the parts, but all latching members must be simultaneously operated.

25 Other and further objects and advantages of the invention will be apparent from the following description when taken in connection with the accompanying drawings, wherein:

30 Fig. 1 is a view in perspective of a connector box or socket constructed in accordance with the invention.

Fig. 2 is a view in perspective of a special tool for unlatching parts of the box to permit removal or insertion of the tubes.

35 Fig. 3 is a longitudinal vertical section taken substantially along the line 3—3 of Fig. 1.

Fig. 4 is an enlarged transverse vertical section taken along the line 4—4 of Fig. 3.

40 Fig. 5 is a fragmentary view in perspective showing the box parts in separated relation and the manner of effecting their separation.

Fig. 6 is a view in perspective of a connector box or socket constructed in accordance with the invention for connecting adjacent tube sections at a corner or in angular succession.

45 Fig. 7 is a fragmentary longitudinal vertical section illustrating the operation of the special tool in releasing the latching members.

Fig. 8 is a longitudinal vertical section similar 50 to Fig. 3 and illustrating a construction of the box or socket by which adjacent tube sections are electrically connected in series upon insertion into the box or socket.

Fig. 9 is a view in perspective of a connector box or socket embodying the invention for sup-

plying power to a single tube or to the desired one of a series of tubes.

Fig. 10 is a longitudinal vertical section taken substantially along the line 10—10 of Fig. 9.

Fig. 11 is a view in perspective of a connector box embodying the invention and for use as in input box.

Fig. 12 is a transverse vertical section taken substantially along the line 12—12 of Fig. 11.

Fig. 13 is a view in perspective of a modified form of connector box particularly adapted for use where the length of the mounting space is relatively small.

Fig. 14 is a fragmentary plan view of the box shown in Fig. 13 with the cover removed.

It is common practise to electrically connect the ends of adjacent tube sections of a high voltage gaseous discharge tube installation by a short lead and to slip a glass bottle over this lead and the abutting ends of the adjacent tube sections. This bottle is merely slipped over the tube sections and may be readily slipped off either intentionally or inadvertently while dusting or cleaning the tubes and is also frequently displaced by the mechanical vibration of the tubes so that the adjacent terminal tips and the connecting lead are left exposed and unprotected. A great many serious accidents have been caused by persons inadvertently, and sometimes intentionally, contacting an exposed terminal tip of a tube section connected in this fashion. The extreme likelihood of these occurrences is evident from the fact that in many installations the tube is exposed in a cove or channel near the ceiling and that in climbing a ladder or stepping upon some other support, a person will place his hands over the edge of the cove or channel for assistance or support. In so doing, his fingers come in contact with the tube and if it happens to be an exposed terminal tip of a tube section, he receives a tremendous shock, knocking him to the floor and seriously injuring or even killing him.

Electrical repair men are prone to slip the bottle off the abutting ends of the adjacent tube section where one section has failed for the purpose of testing or removing a tube section and, in so doing, their hands contact the connecting lead, or a live terminal tip, resulting in serious or fatal injury to the repair men.

The tubes are frequently mounted on a sign surface, mounting panel or window which requires cleaning more or less frequently. Persons who do this cleaning usually have no knowledge of the dangers incident to a contact with a live terminal tip of a tube section and therefore make no effort to avoid such a contact. In fact, in many cases, it has been found that such workmen will slip the bottle off the tip in order to clean the ends of the tube or the bottle. It can be seen, therefore, that the customary practise or manner of mounting and connecting high voltage gaseous discharge tubes is very unsafe. A connector box or socket constructed in accordance with applicant's invention eliminates these dangers and at the same time retains the advantages inherent in the use of the glass bottle, chief among which is that it permits connection of the tube sections without the formation of a dark spot between the sections.

As shown in Fig. 1 of the drawings, a general form of connector box or socket, in accordance with the invention, may comprise an open top box member 2, preferably of insulating material and preferably a one piece molding of

Bakelite or suitable ceramic material. The open top box member 2 comprises a base plate 4 formed integrally with side walls 6 and 8, end walls 10 and 12, and mounting projections 14 and 16 extending outwardly from the opposed end walls 10 and 12.

The base 4 is relatively thin throughout the major portion of its length and is thickened as at 18 and 20 somewhat adjacent the opposite end walls to provide a mounting base for the generally U-shaped spring clips or terminals 22 and 24, which may be secured to the portions 18 and 20 of the base by headed screws or studs 26 and 28 that are preferably held to the base by being molded therein, but may be received in internally threaded sleeves molded in the base as shown in Fig. 8.

Coil springs 30, Fig. 4, secured between the head of each screw 26 or 28 and the base of the terminal clip 22 or 24 projects outwardly between the arms of the clip and provides means for establishing electrical connection with the terminal tip 32 of tube section 34 or with terminal tip 36 of the adjacent tube section 38.

The side walls 6 and 8 of the box member 2 have centrally thereof upwardly extending portions 40 and 42 each defined by oppositely extending edges 44 and 46 to facilitate ready and rigid interlocking of the cover member 48 with the box member 2. Flanges 50 extend inwardly from the upper edges of the portions 40 and 42 to partially close the open top of the box member 2 centrally thereof, but leaving a space therebetween sufficient to accommodate the tube sections.

The upper edges 52 of the end walls 10 and 12, the upper edges 54 of the side walls 6 and 8, the edges 44 and 46 of the central side wall portions 40 and 42, and the end edges 56 of the flanges 50 are bevelled inwardly for mating relation with the similar but oppositely bevelled or tapered edges 58, 60, 62 and 64 of the cover members 48 to insure accurate positioning of the cover member on the box member 2 and to facilitate the ready positioning of the cover

members on the box member in rigid interlocking relation. As additional means for insuring rigid interlocking of the cover members with the box member, the box member at the four corners formed by the junction of the side and end walls 50 is cut away or recessed as at 66 to receive similarly shaped projections 68 formed on the cover member, and at the junction of the flanges 50 with the side wall portions 40 and 42 recesses 70 are formed to receive similarly shaped projections 72 formed on the cover members 48.

Each cover member 48 comprises a top wall portion 74, side wall portions 76 and 78, and an end wall portion 80 shaped to conform to the portion of the box member 2 with which the cover member interfits as previously described.

Means for latching the cover members to the box members comprises sets of latching members 82 and 84 of suitable resilient material or metal strip, preferably generally of inverted J-shape in elevation. The latch members 82 and 84 are preferably formed as the furcations of a bifurcated plate 86, molded in the thickened end portion 88 or 90 of the base 4 and anchored therein as by the laterally bent bottom portion 92. The

latch members 82 and 84 of each set engage the latching shoulder or keeper 94 formed in the inner surface of the end walls 80 of the cover members. Spaced openings 96 are formed in the end wall 58 of each cover member in alignment with the latch members 82 and 84, the openings 75

being less in width than the latch members 82 and 84 so that the latch members may at the sides of the openings engage the latching shoulder or keeper 94. The openings 96 are of the proper dimensions to receive the spaced prongs or blades 98 of a special latch operating tool 100 (Fig. 2), in which the prongs 98 are secured to a handle 102 in proper spaced relation to conform to the spacing of the openings 96 in the end wall 80 of a cover member. It will be seen that the prongs 98 when inserted through the openings 96 will engage the spaced latch members 82 and 84 as shown in Fig. 7 and move these resilient latch members inwardly out of engagement with the latch shoulder or keeper 94 so that the outer end of the cover member may be lifted by means of the tool from an outer end of the box member 2 and the cover member then moved outwardly slightly longitudinally of the box member to release the bevelled edge 64 and the projections 12 of the cover member from the overlying flange 50 and the recess 70.

One of the members of the connector box, preferably the box member 2, is formed with integral flanges or partitions 102 and 104 so spaced from the end of the member as to form with the end and side walls of the cover member a housing or chamber for the latching members which housing or chamber is separate from the housing portion or chamber for the tube sections. Thus the flanges or partitions 102 and 104 prevent anything inserted in the opening or openings 96 from being projected into the housing or chamber for the tube sections and prevents the engagement of any such inserted articles or the prongs of the special tool from being brought into contact with the terminal tips of the tube sections or the terminal clips. Also the flanges or partitions 102 and 104 prevent the occurrence of any electrical discharge between the terminal tips of the tube sections or the terminal clips and the metallic latch members 82 and 84 as will be evident.

Further to insure efficient electrical contact between the terminal tips of the tube sections and the terminal clips whenever the cover members are in box-closing position, the cover members may be provided with downwardly extending projections or lugs 105 formed integrally with the cover members in positions to overlie and engage the terminal tips 32 and 36 of the tube sections 34 and 38, thereby forcing the terminal tips downwardly into efficient electrical contact with the terminal clips and the springs 30 and preventing release of the terminal tips from the terminal clips due to vibration or any other cause.

In installations of such high voltage gaseous discharge tubes, it is found that electrical charges accumulate upon the proximate ends of adjacent tube sections causing radio interference currents between the tube sections, which being in the range of audible frequencies, are particularly annoying to listeners of radios in the vicinity of such installations and being audible, are also annoying by their monotony to people who must remain in the vicinity of the installation for any appreciable length of time. Accordingly applicant provides in his connector box or socket a shielding metal plate or screen 106 arranged centrally of the connector box and preferably molded in the base 4 to extend upwardly from the base between and above the flanges 50 and to extend, when the tube sections are inserted in the box, between the proximate ends of the tube sections. This shielding plate may be grounded in a de-

sired manner as, for example, as shown in Figs. 11 and 12.

In Fig. 6 is shown a similar connector box for mounting and electrically connecting adjacent tube sections at a corner of the room or other space. As shown in this figure, the box member 108 is formed of wings 110 and 112 disposed at the desired relative angle and connected by the opposite curved side walls 114 and 116 between which along their common radius extends the shielding plate or screen 118 similar to the screen or plate 106.

The box member 108 may otherwise be identical in construction with the box member 2 and be closed by the detachably latched cover members 120 identical in construction to the cover members 48.

To facilitate the serial connection of adjacent tube sections, the connector box or socket may have mounted or molded therein a connecting strip or bar 122 as shown in Fig. 8, which preferably is mounted or molded in the base or bottom wall 124 of the open top box member 126. The connector strip 122 may be preassembled with internally threaded sleeves 128 which receive the mounting screws 26 and 28 for the terminal clips 22 and 24. It will be seen that by the mere act of inserting the adjacent tube sections, such sections are electrically connected in series.

In Figs. 9 and 10 there is shown a form of the connector box or socket for use in mounting one end of a single tube installation or the end tube section of a multi-section installation in which the sections do not form a closed geometrical configuration. As shown in these figures, the connector box or socket comprises a single cover member 48 received upon and enclosing a box member 130. The box member 130 has a bottom plate or wall portion 132, side walls 134 and 136, and opposed end walls 138 and 140. The end wall 138 is formed similarly to the end wall 10, but the end wall 140 extends from the base 132 to the upper edge of the connector box and in the plane of the flanges 142 which extend inwardly from the opposed wall portions 144 and 146 which are defined by the end wall 140 and the inclined edges 148. The single cover member 48 is interlocked with and latched to the box member 30 in the same manner as each of the cover members 48 in the form shown in Figs. 1 to 8 is interlocked with and latched to the box member 2, 108, or 126. The box member 130 is also provided with oppositely extending mounting portions or lugs 150 similar to the mounting means or projections 14 and 16. The electric current may be supplied to the terminal clip 152 which is similar to the terminal clip 22 and 24 by means of an input lead 154 more particularly hereinafter described with reference to the input connector box shown in Figs. 11 and 12.

Figs. 11 and 12 shows the connector box as formed for use as an input box by which the leads from the source of electricity may be connected through the ends of adjacent tube sections. As shown in these figures, the input leads 154 and 156 extend into the box member 2 through the side wall 8 and the bottom wall portion 4 in openings 158 for connection to the mounting screws 26 or 28 for the terminal clips 22 or 24 to which the leads are fastened in any suitable manner as by nuts 160 which may be manipulated, to fasten or release the lead through an opening 162 in the bottom wall portion 4. The

opening 162 may be closed by a plug 164 threaded directly into the base or into an internally threaded sleeve molded in the base. The lead 154 or 156 which may be housed within the usual pipe or BX armor by a BX connector 166 molded in the connector box and fastened and electrically connected to the rounded pipe or BX armor 168 by the usual set screw 170. The shield 106 may be grounded by a lead extending from the shield to the BX connector 166. Preferably, however, a pin 172 is threaded or molded in the box 2 and extends outwardly thereof through the side wall 8 to provide a terminal pin which may be grounded as shown in Fig. 11.

In the form shown in Figs. 13 and 14, a connector box similar to that shown in Figs. 9 and 10 is formed of an open top box member 174 of double width with a longitudinal partition 176 extending from a transverse partition 178. The partition 176 extends partially or entirely the length of the box member 174 to form spaced chambers 180 and 182 for receiving the adjacent tube sections 184 and 186 in laterally spaced relation. The terminal clips 188 and 190 similar to the terminal clips 22 and 24, are similarly mounted in the chambers 180 and 182 and may be connected by a conducting strip 192 molded into the box member 174 beneath the clips. In this form the adjacent tube sections 184 and 186 extend in longitudinally overlapping relation as shown in Fig. 13 so that the line of light from the tubes appears, even when looked at directly, as continuous. In order to permit this longitudinal overlapping of the adjacent tube sections, with a connector box of the minimum length, the cover member 192 which is similar to the cover member 48, but of double width, is inwardly from its open end slotted as at 194 for reception of the downwardly curved end portion of the tube section 186. In this form of connector box, the resilient latch members 196 and 198, which are similar to the latch members 82 and 84, are spaced apart a greater distance to securely latch the double width cover member 192. The openings 200 through the end wall 202 of the cover member 192 are similarly spaced apart a greater distance to receive the similarly spaced latch receiving prongs of the special box opening tool. The connector box shown in Figs. 13 and 14 may otherwise be formed identically with the connector box as shown in Figs. 1 to 12.

When such a box as shown in Figs. 13 and 14 is to be used as a power input box, the connecting strap 192 will be eliminated and input means such as shown in Figs. 11 and 12 may be provided for connection to the terminal clips, but such input means would of course be disposed on opposite sides of the connector box shown in Figs. 13 and 14.

It will therefore be seen that applicant has provided a connector box or socket for high voltage gaseous discharge tubes which is simple and inexpensive from the manufacturer's standpoint; which is capable of ready mounting in any place where such tubes may be used, and of such construction that it may be used in exposed places without detract from the appearance of the tube installation.

The invention also provides a connector box offering the maximum of protection against possibility of any article inadvertently or intentionally being brought into contact with the tube supplying terminals or connecting leads, and precluding the possibility of any unauthorized person in-

advertently or intentionally contacting such terminals or connecting leads.

Applicant has further provided a connector box or socket for the gaseous discharge tubes, which box or socket is comprised of parts readily separable for the simple insertion and automatic connection of the discharge tube, and which separable parts are automatically latched against detachment when brought into normal assembled relation, and wherein the separable latching means may be released or unlatched only by means of a special tool thereby preventing access except by those familiar with the construction of the connector box or socket.

Applicant's invention also provides connector boxes or sockets for receiving and connecting in series adjacent lengths of tubing arranged in linear succession or in angular succession.

The invention herein further provides connector boxes or sockets for gaseous discharge tubes by which tube sections may be connected in series or by which power connections may be made to a tube or tube sections.

Applicant has further provided a connector box or socket for adjacent tube sections and in which means is provided for shielding the tubes against accumulation of static charges on adjacent or abutting end portions and thereby eliminating radio interference currents in tube installations and also eliminating the possibility of electrical shock of a person intentionally or inadvertently contacting one or both of abutting end portions of adjacent tube sections.

The invention further provides in a connector box or socket for high voltage discharge tubes means for eliminating dangerous "skin currents" along the tube envelopes, and also thereby increases the life of the tubes.

Applicant has further provided in a connector box or socket of the above stated character, spring clips for receiving and establishing electrical connection with the terminal tips of the discharge tube and wherein means is provided for insuring the maintenance of electrical connection regardless of all mechanical vibration of the tube or socket relative to each other.

The invention further provides a connector box or socket of the above stated character which is comprised of relatively separable parts which, when brought into assembled relation, are automatically latched against detachment by a multiplicity of latching members so that operation of one of the latching members will not permit separation of the parts, but all latching members must be simultaneously operated.

It is obvious that various changes may be made in the specific embodiments of the invention set forth for purposes of illustration without departing from the spirit of the invention. Accordingly the invention is not to be limited to the specific embodiments shown and described but only as indicated in the following claims.

The invention is hereby claimed as follows:

1. A socket for gaseous discharge tubes comprising an elongated box member having relatively long bottom and side wall portions and relatively restricted end walls adapted to receive the elongated extremity of a discharge tube in coaxial relationship with the longitudinal axis of said box, the top wall of the box comprising a detachable cover adapted to interfit with the box member and to extend over the end of the tube, said cover having one longitudinal extremity cut away and providing an opening in the top of the box when the cover is in opera-

tive position whereby the cover partially closes the open wall of the box member and provides an opening for a laterally extending portion of the discharge tube and permitting passage outwardly of the box, and a resilient electrical terminal clip mounted in the box member below said cover to receive and resiliently clamp the tube terminal.

2. A socket for gaseous discharge tubes comprising an elongated box member having relatively long bottom and side wall portions and relatively restricted end walls adapted to receive the elongated extremity of a discharge tube in coaxial relationship with the longitudinal axis of said box, the top wall of the box comprising a detachable cover adapted to interfit with the box member and to extend over the end of the tube, said cover having one longitudinal extremity cut away and providing an opening in the top of the box when the cover is in operative position whereby the cover partially closes the open wall of the box member and provides an opening for a laterally extending portion of the discharge tube and permitting passage outwardly of the box, and a resilient electrical terminal clip mounted in the box member below said cover to receive and resiliently clamp the tube terminal, a projecting means on said cover opposite the clip and constructed and arranged to engage the end of said tube when in operative position in the clip whereby to lockingly hold the tube against movement.

3. A socket for gaseous discharge tubes comprising an elongated box member having relatively long bottom and side wall portions and relatively restricted end walls adapted to receive the elongated extremity of a discharge tube in coaxial relationship with the longitudinal axis of said box, the top wall of the box comprising a detachable cover adapted to interfit with the box member and to extend over the end of the tube, said cover having one longitudinal extremity cut away and providing an opening in the top of the box when the cover is in operative position whereby the cover partially closes the open wall of the box member and provides an opening for a laterally extending portion of the discharge tube and permitting passage outwardly of the box, and a resilient electrical terminal clip mounted in the box member below said cover to receive and resiliently clamp the tube terminal, means projecting from the inner surface of said cover opposite said clip and adapted to interengage the end of said tube for holding the tube against movement, said clip including resilient means engageable with the underportion of the tube terminal and operative to urge the tube terminal toward the cover for resiliently gripping the terminal against said cover projection.

4. A socket for adjacent tube sections of a gaseous discharge tube installation, said socket comprising an elongated box-like base member having relatively elongated bottom and side wall portions and relatively restricted end walls and an open top wall portion to receive through the open top wall the terminal-carrying ends of adjacent tube sections, spaced electric terminals mounted in said base member adjacent opposite ends thereof and projecting from the bottom wall of the base member to receive the terminals of the tube sections disposed longitudinally within the base member, and a detachable cover having a top wall and depending side and end walls adapted to interfit with the side and end walls of the base member and to extend over the

ends of the adjacent tube sections, said base member being of greater length than said cover and the side walls of the base member having portions extending beyond said cover and of greater height, with their upper edges flush with the top wall of said cover whereby the cover only partially closes the open top wall of said base member to permit passage of the tubes out of the base member between said side wall portions of greater height.

5. A socket for adjacent tube sections of a gaseous discharge tube installation, said socket comprising an elongated box-like base member having an open wall to receive through the open wall terminal carrying ends of adjacent tube sections in longitudinally spaced relation, longitudinally spaced electric terminals mounted in said base member to receive the terminals of the tube sections, and separate individually detachable cover members adapted to interfit with the base member in longitudinally spaced relation and to extend over the ends of the tube sections and partially close the open wall of said base member, said base member having central side wall portions extending between said cover members with the upper edges of said portions substantially flush with the surface of said cover members whereby to permit passage of the tube sections out of the socket between the central side wall portions of said base member when the cover members are interfitted with the base member.

6. A socket for gaseous discharge tubes as defined in claim 1, having a second cover longitudinally spaced on said box member and providing at its longitudinal extremity a second aperture in said cover for a laterally extending portion of a second discharge tube member, a second longitudinally spaced electrical terminal beneath said second cover and electrostatic shielding means disposed therebetween.

7. A socket for adjacent tube sections of a gaseous discharge tube installation, said socket comprising a box-like base member having an open wall to receive through the open wall the terminal carrying ends of adjacent tube sections, spaced electric terminals mounted in said base member to receive the terminals of the tube sections, detachable cover means adapted to interfit with the base member over the ends of the adjacent tube sections and partially close the open wall of said base member to permit passage of the tubes out of the base member through the unclosed portion of said wall, and an electrostatic shield formed of conducting material mounted in the base member and disposed to project between adjacent tube sections comprising means for connecting said shield to ground.

8. An input socket for gaseous discharge tubes comprising a box-like base member having an open wall to receive through the open wall the terminal carrying end of the tube, an electric terminal mounted in said base member to receive the tube terminal, a detachable cover member adapted to interfit with the box member and extend over the end of the tube and partially close the open wall of said box member to permit passage of the tube out of the box member through the unclosed portion of said wall, means within the base member for fastening an input power lead to said electric terminal, and said base member having angularly related openings to receive the input lead and to permit manipulation of the fastening means to secure said means to the electric terminal.

9. A socket for adjacent tube sections of a gaseous discharge tube installation, said socket comprising a box-like base member having a longitudinally extending open wall to receive through the open wall the laterally spaced terminal carrying ends of adjacent tube sections, laterally spaced electric terminals mounted in said base member to receive the laterally spaced terminal ends of adjacent tube sections, and a common detachable cover member interfitting with the base member and extending over the laterally spaced ends of the adjacent tube sections, said cover member partially closing the open wall of said base member to permit passage of the tube sections out of the member through the unclosed portion of said wall and in laterally spaced longitudinally overlapping relation.

10. A socket for gaseous discharge tubes comprising a box-like base member having opposed side and opposed end walls, portions of said opposed side walls being of less height than the remaining portions of said side walls and one end wall being of less height than the opposite end wall, terminal means mounted in and projecting from said base member to detachably receive the terminal end of a gaseous discharge tube and establish electric connection therewith, a cover less in length than said base member, said cover having a top wall, opposed side walls and one end wall, said opposed side walls and said end wall interfitting with the side wall portions of less height of said base member and with the end wall portion of less height of said base member to extend in planes flush with the opposed side walls and said end wall of less height and

5 with the top wall of the cover flush with the upper edges of the side wall portions of greater height of the base member, said cover member terminating short of the end wall of greater height of the base member to provide an opening to permit passage of the tube out of the socket.

11. A socket for gaseous discharge tubes comprising a box-like base member having opposed side and opposed end walls, portions of said opposed side walls being of less height than the remaining portions of said side walls and one end wall being of less height than the opposite end wall, terminal means mounted in and projecting from the base member adjacent the end wall portion of less height, to detachably receive the terminal end of a gaseous discharge tube and establish electrical connection therewith, a cover less in length than said base member, said cover having a top wall, opposed side walls and one end wall, said opposed side walls and said end wall interfitting with the side wall portions of less height of said base member and with the end wall portions of less height of said base member to extend in planes flush with the opposed side walls and said end wall of less height and with the top wall of the cover flush with the upper edges of the side wall portions of greater height of the base member, said cover member, at its end adjacent the said end wall of greater height being provided with a cutaway portion to provide an opening to permit passage of the tube out of the socket.

ROBERT E. BARCLAY.
